CLAIM

The ornamental design for a flexible implant as shown and described.

DESCRIPTION

FIG. 1 is a front perspective view of the design of the present invention for a flexible implant;

FIG. 2 is a front view of the flexible implant illustrated in FIG. 1;

FIG. 3 is a rear view of the flexible implant illustrated in FIG. 1;

FIG. 4 is a left-side view of the flexible implant illustrated in FIG. 1;

FIG. 5 is a right-side view of the flexible implant illustrated in FIG. 1;

FIG. 6 is a top view of the flexible implant illustrated in FIG. 1; and,

FIG. 7 is a bottom view of the flexible implant illustrated in FIG. 1.

The broken lines in the drawings illustrate portions of the flexible implant that form no part of the claimed design.

1 Claim, 6 Drawing Sheets
